UNITED STATES PATENT OFFICE.

CHARLES E. DURYEA, OF SAGINAW, MICHIGAN.

DRIVING MECHANISM.

1,244,185.

Specification of Letters Patent.

Patented Oct. 23, 1917.

Application filed June 26, 1912. Serial No. 705,962.

To all whom it may concern:

Be it known that I, CHARLES E. DURYEA, a citizen of the United States of America, and resident of Saginaw, in the county of Saginaw and State of Michigan, have invented certain new and useful Improvements in Driving Mechanism, of which the following is a specification.

This invention relates to certain new and useful improvements in driving mechanism for motor driven vehicles and it has for its objects among others to provide a simplified form of driving mechanism which shall have a wide range of speeds, as for service where the load may be heavy and the speed preferably slow, and also to provide a range of high speeds under normal working conditions, and further to provide a mechanism so simple in its nature as to give the minimum amount of trouble and not liable to injury or derangement of parts.

Other objects and advantages of the invention will hereinafter appear and the novel features thereof will be particularly pointed out in the appended claims.

The invention is clearly illustrated in the accompanying drawings, which, with the numerals of reference marked thereon, form a part of this specification, and in which— Figure 1 is a plan of the rear frame or chassis of the vehicle with portions broken away showing substantially one half of the parts, it being understood that the propelling wheels upon opposite sides of the vehicle are driven by identical mechanism, being a duplicate of that shown in Fig. 1.

Fig. 2 is a sectional detail of the drum and its crank shaft.

Fig. 3 is a detail of the operating lever and link detached.

Fig. 4 is a side elevation with a portion of the frame and the propelling wheel broken away.

Fig. 5 is a sectional view through the housing showing the large and small pinions therein.

Fig. 6 is a section on the line 6—6 of Fig. 5.

Fig. 7 is a detail in elevation with the shaft in section showing two positions of the friction gear or roller.

Fig. 8 is a cross section on the line 8—8 of Fig. 3.

Like numerals of reference indicate like parts throughout the several views.

Referring to the drawings in which I have

chosen to show my present invention as applied to a two-cycle engine, 1 designates the fly wheel disposed between the engines thereof, one of the cylinders being shown at 2 with its corresponding crank case 3, and with the crank shaft 4 projecting and carrying the transmission drum 5. While it is understood that these engines may be of any preferred kind, I have shown, for the purpose of illustration in this application, simply the cylinder and crank case as might be employed by an engine of the two-cycle type, but without limiting myself to the employment of the invention in connection with such particular kind of engine, but reserve the right to use the same in connection with any type of motor, whether internal combustion, steam, or electric, and whether of one or more cylinders or moving elements.

The drum 5 is shown in section in Fig. 1 and also in section upon a larger scale in Fig. 2, the latter view showing a portion of the crank shaft by which it is carried. This drum carries two concentric internal gears, 6, the smaller one, 6, being nearest the engine, and the large one, 7, being at the mouth of the drum. Adapted to engage these internal gears is a spur pinion 8, which is slideable along the shaft 9, by suitable shifting means (not shown), and splined to the shaft so as to compel the shaft 9 to turn with the pinion 8. Normally this pinion meshes into the internal gear 6, concentrically and with the same number of teeth, so that the shaft 9 revolves with the crank shaft 4.

In this system of propulsion I employ a friction ring or gear 11, attached to the propelling wheel 12 of the vehicle, in any suitable manner, and grooved on both its inner and outer curved surfaces, these grooves being circumferential and of suitable size for friction gears. Into this large ring gear I arrange to mesh a large driving pinion 10 carried on the end of the shaft 9, near the wheel 12 and in the plane of the ring gear 11.

It is well known that to engage or disengage friction gears of metal, very little movement is required, so that in actual practice, a very slight movement of the pinion 10 toward the inner surface of the ring 11 will bring the two in contact, and if sufficient pressure is applied will cause the engine to propel the wheel 12 with power. To bring the driving pinion 10 into contact with the ring 11, I arrange to swing the outer end of the shaft 9 as a radius around

a point approximately at the center of the pinion 8. To do this I make the frame 13 of my chassis curved into a suitable arc at that portion which supports the bearing 14 for the shaft 9. This bearing 14 is carried on a swiveled slide 15 which is arranged by a suitable means to be thrown forward or backward on the arc by the shifting rod 16, link 17, and the operating lever 18, or 5 by other suitable means. In order to provide a somewhat higher speed, I arrange suitable shifting means to slide the pinion 8 on the shaft 9, away from the crank shaft end until it disengages the internal gear 6, 10 and lies in the plane of the internal gear 7. I then shift it in the plane of the gear 7, until it engages and is driven by said gear at a somewhat faster speed. The shifting means for moving the pinion 8 laterally 15 with respect to the line of progress of the vehicle and then lengthwise the vehicle to engage the internal gear 7, I have not shown, since obvious means can be applied by any 20 mechanic, and this shifting device is not a part of this invention. When the shaft 9, 25 running at higher speed, is to propel the vehicle, the gear 10 is brought into engagement gradually with the ring 11, by means of the operating lever 18 and its connections 30 17 and 16, as before described.

It will be noted that since the shaft 9 in its varying positions of neutral, normal gear, and high gear differs more or less from a position continuous with the cases 35 of the crank shaft, there must be either a universal joint or provision for a universal joint effect, and this I secure by slightly separating the spur teeth of the pinion 8, and the internal gears 6 and 7, so that the 40 slight universal joint action required may be permitted by these teeth. It is, of course, quite evident that at some complication a universal joint could be provided between the crank shaft and the shaft 9, either side 45 of the gearing employed, or without the use of gearing, but my arrangement secures both this universal joint service and a speed of normal and high, by the same mechanism. It is well known that such effects are often 50 secured by the use of a spur pinion meshing into an internal gearing, as I propose, and the slight movement in such a joint is not objectionable.

It is, of course, possible to employ some 55 form of reducing gearing at or near the location of the drum 4, for getting lower speeds, but I prefer to accomplish these, and also a reverse, by the mechanism shown in Figs. 4 to 7 inclusive, particularly shown 60 in detail, sectional elevation, in Fig. 6. As shown here, I mount on the shaft 9, a small pinion 19, and parallel to the shaft 9, in a suitable housing 20, I mount a shaft 21, which has a large gear 22, adapted to be 65 shifted laterally by suitable shifter fork

(not shown), fitting into the shifting slot 21^a in the shaft 21. It will be seen from Fig. 6 that when the pinion 19 and gear 22 are in mesh and driving the shaft 21, the small friction gear or roller 23 will be 70 in the plane of the large driving roller 10, and, therefore, in the plane of the driven ring 11. It is also evident that the shaft 21 will run in a reverse direction to the shaft 9, and so propel the vehicle in a reverse direction if the roller 23 is pressed against the ring 11 on the inside as the roller 10 is normally used. This secures the required reverse movement of the vehicle and the normal position of this roller 23 is shown 80 in Figs. 4 and 7 in full lines. To secure a low speed, however, a somewhat different position is given to the shaft 21, by swinging the housing 20 angularly around the shaft 9 until it is brought into the position 85 shown in dotted lines, Figs. 4 and 7, it being evident that the gears must be thrown out of mesh in order to draw the roller 23 out of the plane of the ring 11 far enough to permit it to pass the ring 11 and get on the 90 outside thereof, in which position the gears are again meshed. Since this arrangement permits the roller 23 being placed in the plane of the ring 11 in the dotted position, it is evident that a rearward movement will 95 carry the large roller 10 farther away from the ring 11, and bring the roller now at dotted position back into contact with the ring 11, and thus drive the vehicle forward at slow speed, somewhat slower than reverse 100 because the outer surface of this ring 11 is longer than the inner surface against which the large roller 10 and the roller 23, in reverse positions, work. It is also evident that the operating lever 18 with its link 105 17, and shifting rod 16 may be used to throw the parts backward just as efficiently as forward. The mechanism for shifting the shaft 21 or swinging the housing 20 is not shown, but suitable studs 25 on the housing, for 110 swinging the housing 20, are shown in Fig. 6. In Figs. 4 and 7, stops or arms 26 and 27 are shown, which limit the angular movement of the housing 20 under the pressure applied by the operator, through the lever 115 18, the link 17 and shifting rod 16, as described.

It will be evident that when the roller 23 is carried toward the inner surface of the ring 11, for reverse motion, the roller 10 120 must not at the same time engage the ring 11, and this is secured by having the stop 26 so placed that the distance between the roller 23 and the ring 11 requires less movement to secure contact, than the greater 125 distance between the roller 10 and the ring 11, and that to engage the roller 10 for normal direct driven speeds, the shaft 21, with its roller 23, must be withdrawn so that the gear 22 is not in mesh with the pinion 19. 130

I have shown the frame of the chassis as terminating in a ball joint 28, which is carried by suitable socket connected with the body of the vehicle, and it is evident that 5 the link 17 must pass at a greater or less distance from this ball center so that as the rear axle 29 of the vehicle rises and falls over obstacles in the road, there will be some tendency to shorten or lengthen the link 17 or its connections and thus produce some 10 variation in the pressure with which the driving rollers engage the driven ring 11. To accommodate this slightly varying motion, I make the lever 18 with a large eye 15 where the link 17 is attached, and fill this eye with rubber, as seen at 31, to carry the pin of the link 17, as is done in rubber lined eyes of vehicle springs. It is, of course, evident that I can provide in the link 17 or in the shifting rod 16, other elastic 20 means, such as springs of some suitable kind mounted either in cases or around telescopic slides as trace springs are sometimes employed in horse harness. There is more 25 or less necessity of this spring action in this construction, owing to the fact that if the operator should shift the pinion 8 from the gear 6 to 7 or vice versa, without releasing the pawl 29 of the operating lever 18 from its rack 30, there would be a much greater 30 strain on the link 17 or much less as might happen, and for which the elastic medium 31 largely compensates.

Modifications in details may be resorted 35 to without departing from the spirit of the invention or sacrificing any of its advantages.

What is claimed as new is:—

1. In a driving mechanism of the character described, a stationary motor, a driving pinion and a loose gearing connection between the shaft of the motor and the driving pinion constructed to permit of swinging movement of the driven end of the shaft 45 of the driving pinion.

2. In a driving mechanism of the character described, a motor and a friction roller drive mechanism combined with variable speed gears coöperating with the shaft of 50 said roller drive mechanism to change the speed, and means to effect swinging movement of the driven end of the roller drive mechanism shaft.

3. In a driving mechanism of the class 55 described, a driven wheel, a single large ring carried by said driven wheel, and a friction drive roller, a shaft carrying said roller mounted to allow of coöperation of said roller with the inner or outer surfaces 60 of said ring, and means to effect swinging movement of the driven end of the shaft of said roller.

4. In a driving mechanism of the class 65 described, a shaft mounted to swing, a friction drive roller carried by one end of said

shaft, a transmission drum with concentric internal gears, and a pinion mounted for sliding movement on said shaft for coöperation with either of said gears.

5. A motor, its shaft, a secondary shaft 70 adapted to be actuated therefrom, coöperating gears carried by said shafts embodying a loose gear connection and swiveled means for moving one of the shafts and its gear to bring the latter into operative relation 75 with the other gears.

6. In a driving mechanism of the class described, a frame having an arc portion, a shaft, and a longitudinally disposed bearing therefor slidingly swiveled on said arc portion. 30

7. In a driving mechanism of the class described, a motor, an auxiliary shaft, a frame having a longitudinally disposed arc portion, a slide mounted for movement on the arc portion, and a bearing for said shaft carried by said slide, and a connection between said motor and said auxiliary shaft. 35

8. In a driving mechanism of the class described, a motor, an auxiliary shaft, a frame having a longitudinally disposed arc portion, a swiveled slide mounted for movement on the arc portion, and a bearing for 90 said shaft carried by said slide, and a connection between said motor and said auxiliary shaft. 95

9. In a driving mechanism of the class described, a swiveled slide, an operating lever, a shifting rod, and a link, said lever having an enlarged opening receiving the 100 end of said link, and an elastic tension device in said opening embracing the end of said link.

10. In a driving mechanism of the class described, a motor and its crank shaft, a 105 transmission drum carried by said crank shaft, an auxiliary shaft, a swiveled slide, and a bearing for said auxiliary shaft carried by said slide, and a connection between said motor and said auxiliary shaft. 110

11. In a driving mechanism of the class described, a motor and its crank shaft, a transmission drum carried by said crank shaft, an auxiliary shaft, a swiveled slide, a bearing for said auxiliary shaft carried by 115 said slide, and a connection between said motor and said auxiliary shaft, an operating lever, a shifting rod, and a link provided with an elastic tension device.

12. In a driving mechanism of the class 120 described, a motor, its crank shaft and a transmission drum carried thereby, an auxiliary shaft, a swiveled slide, a bearing for the auxiliary shaft carried by said slide, and a connection between said motor and 125 said auxiliary shaft, an operating lever having an eye, a link attached to said eye, and resilient means filling said eye receiving the pin of the link.

13. In a driving mechanism of the class 130

- described, a shaft, a driving pinion carried thereby, a transmission drum having inner and outer internal gears, a pinion for co-operation with said gears, there being an interposed loose intermeshing connection between said last-named pinion and gears, and a bearing for said shaft mounted to swivel for swinging the shaft to bring an end thereof and its pinion into operative relation with said gears.
14. In a driving mechanism of the class described, a shaft, a driving pinion carried thereby, a transmission drum having inner and outer internal gears, a pinion for co-operation with said gears, there being an interposed loose intermeshing connection between said last-named pinion and gears, and a bearing for said shaft mounted to swivel for swinging the shaft to bring an end thereof and its pinion into operative relation with said gears, and a swiveled slide, said bearing being carried by said slide.
15. In a driving mechanism of the class described, a motor, a transmission drum, an auxiliary shaft and interposed gears, a movably mounted shaft, a pinion on the last-named shaft, and a pinion on the auxiliary shaft, and friction drive members carried by said shafts.
16. In a driving mechanism of the class described, a transmission drum, a shaft and interposed gears, a movably mounted shaft, intermeshing gears on the last-named shaft and the first-named shaft, friction drive members carried by said shafts, said friction drive members being grooved, the propelling wheel and a ring grooved upon its inner and outer surfaces and carried by said propelling wheel.
17. In a driving mechanism of the class described, friction gears, coöperating gears, a shaft carrying one of said friction gears and having loose connection interposed between the same and the coöperating gears, a shifting lever, a connecting member, and an interposed elastic device.
18. In a driving mechanism of the class described, a driven ring and a driving roller coöperating therewith, a shaft for the latter mounted in an adjustable bearing, means to effect swinging movement of the driven end of said roller shaft and means for moving said bearing to vary the pressure with which the driving roller engages the driven ring, said means embodying an elastic device interposed between two of the members of said moving means.
19. In a driving mechanism, a stationary motor, transmission mechanism, and a connection between the motor shaft and such mechanism embodying a loose internal and external gear connection permitting swinging movement of an end of the shaft of the transmission mechanism.
20. In a driving mechanism, a motor, a transmission gearing, and a connection between the motor shaft and said gearing embodying a driven shaft and means movable to cause swinging movement of the driven end of said shaft to bring a gear carried by said shaft into operative relation with either of the coöperating gears on the motor shaft.

Signed by me at Saginaw, Michigan, this 24th day of June, 1912.

CHARLES E. DURYEA.
